UNITED STATES PATENT OFFICE

CHARLES W. MUELLER, OF ST. LOUIS, MISSOURI, ASSIGNOR TO LEWIS INVISIBLE STITCH MACHINE COMPANY, OF ST. LOUIS, MISSOURI, A CORPORATION OF MAINE

DESIGN FOR A SEWING MACHINE FRAME

Application filed August 31, 1929. Serial No. 32,636. Term of patent 14 years.

To all whom it may concern:

Be it known that I, CHARLES W. MUELLER, a citizen of the United States, residing at St. Louis, State of Missouri, have invented a new, original, and ornamental Design for Sewing-Machine Frames, of which the following is a specification, reference being had to the accompanying drawing, forming part thereof.

The figure is a perspective view of the article, showing my new design.

I claim:

The ornamental design for a Sewing Machine Frame, as shown.

CHARLES W. MUELLER.
